UNITED STATES PATENT OFFICE

170,085

FARE BOX

Max L. Grant, Providence, R. I.

Application May 25, 1951, Serial No. 15,314

Term of patent 14 years

(Cl. D52—4)

To all whom it may concern:

Be it known that I, Max L. Grant, a citizen of the United States, residing at Providence, in the county of Providence, State of Rhode Island, have invented a new, original, and ornamental Design for a Fare Box, of which the following is a specification, reference being had to the accompanying drawing, forming a part hereof.

Fig. 1 is a perspective view of a fare box, showing my new design, the side and the rear of the fare box, not disclosed, are substantially plain in appearance;

Fig. 2 is a top plan view of Fig. 1.

I claim:

The ornamental design for a fare box, as shown and described.

MAX L. GRANT.
